UNITED STATES PATENT OFFICE.

CHARLES ANDREWS, JR., OF ROCKFORD, ILLINOIS, ASSIGNOR TO ANDREWS WIRE & IRON WORKS, OF ROCKFORD, ILLINOIS, A CORPORATION OF ILLINOIS.

DESIGN FOR A FRAME FOR OVENWARE.

58,206.

Specification for Design. Patented June 28, 1921.

Application filed November 21, 1919. Serial No. 339,728. Term of patent 7 years.

To all whom it may concern:

Be it known that I, CHARLES ANDREWS, Jr., a citizen of the United States, residing at Rockford, in the county of Winnebago and State of Illinois, have invented a new and original and ornamental Design for a Frame for Ovenware, of which the following is a specification, reference being had to the accompanying drawing, forming a part thereof.

In the drawing,—

Figure 1 is a plan view of a frame for ovenware, showing my new design; Figs. 2 and 3, side and end views respectively thereof.

I claim:

The ornamental design for a frame for ovenware, as shown.

CHARLES ANDREWS, JR.
